UNITED STATES PATENT OFFICE

THOMAS M. ROYAL, OF PHILADELPHIA, PENNSYLVANIA

METHOD OF MAKING PAPER BAGS

Application filed February 7, 1929. Serial No. 338,075.

My invention relates to the art or method of making paper bags, particularly bags of the character in which either the inside or the outside or both the inside and outside are provided with a coating of one substance or another, as may be selected. Wax may be mentioned as one substance which is quite generally employed as a coating for one surface or the other of bags to render them moisture proof and also impervious to grease. The latter is desirable if the bags are employed for holding greasy objects; for example, potato chips. The invention is not dependent upon the substance of the coating, because such substances may vary at the election of the manufacturer and also may be varied to meet conditions as they may arise; neither is the invention limited to the uses for which the bags may be employed after they have been manufactured. Wax, paraffin, and other like substances may be employed to form the coatings.

The general object of the present invention is to provide a novel and improved method in the manufacture of bags whereby in the process of manufacturing the same one side or the other, or both sides, if the manufacturer should so elect, is or are provided with a coating of a suitable substance, such as wax.

It also is an object of the invention to provide a novel method in the manufacture of bags of paper or other suitable flexible material wherein wax or other suitable substance is applied as a coating at intervals to portions of either one or both sides of a web of paper, the coating being omitted from other parts of the said web in adjoining lateral relation to one edge of each of the portions or sections of coating which may be applied.

Without further stating the objects of the invention it may be set forth that the invention comprehends broadly a method wherein and whereby coatings of a suitable substance, such as wax, are applied at intervals to a web of paper in such manner as not to interfere with the uniting of the edges of the web of paper and of other portions

thereof in the formation of the bag structure.

By reference to the drawing which accompanies this specification and forms a part thereof the invention and the underlying principle thereof will be readily understood as the description proceeds.

In the drawing,

Fig. 1 is a plan view of a fragmentary portion of a web of paper on the exposed surface of which sections of a coating of wax or the like are shown at spaced intervals;

Fig. 2 is a similar view in which in addition to the portions of coating a strip of adhesive is shown along the margin of one side of the web or sheet, which margin is free from coatings of wax;

Fig. 3 is a view in perspective of a fragmentary portion of a tubular section showing the manner in which the opposite side portions of the web are folded over, with their marginal edge portions in overlapped relation and indicating the manner in which the said marginal edge portions are secured together;

Fig. 4 is a view in perspective of a section of a tubular portion like that indicated in Fig. 3, the said section being formed by severing the tubular structure in the intervals between adjoining coated portions, and the said view also showing a strip of adhesive along one end portion thereof;

Fig. 5 is a view in perspective of a bag formed by folding over one end portion of the tubular section shown in Fig. 4; and

Fig. 6 is a view in perspective of a fragmentary portion of a tubular structure indicating a coating of a suitable waterproofing substance at spaced intervals upon both the inner and outer sides of the said tubular structure.

In the manufacture of paper bags commercially in accordance with the art or method of my invention, machines known in the art as paper bag machines or bag-forming machines will be employed, but as the art or method may be carried out manually I have elected not to encumber the disclosure by the showing of a machine which, no matter how sketchily or diagrammatically it may

be illustrated, would lend more or less of complication to the description of the invention. On the contrary, I have chosen to illustrate the invention in the simplest possible way by reference only to the web or sheet of paper or other material and the areas thereof to which the coating of wax or other equivalent substance is applied and the relation of those areas to each other and the smaller areas from which the coating is omitted.

In the drawing I have shown a fragmentary portion of a web of paper 1 to portions of one surface of which, as illustrated in Figs. 1 to 4 of the drawing, a coating 2 of a suitable material, such as wax, is applied. The coatings are applied to the web 1 at spaced intervals, as shown. The spaces 3 between the successive and adjoining sections of coating are of such width as may be necessary to permit severing of the web, after its formation into a tubular structure, in the manner common to the manufacture of paper bags without cutting into the coated areas. It will be noted that the area of each of the sections of coating 2 is of less width than the width of the web 1, so that a marginal edge portion 4 of one side of the web is free from the coating. A narrow strip of adhesive 5 is applied continuously along the uncoated marginal edge portion 4 of the web in parallel relation to the adjoining edges of the sections of coating 2. The relation of the sections of coating 2 to the strip of adhesive 5 is clearly illustrated in Figs. 2 and 3 of the drawing.

The sections of coating having been applied at intervals, as illustrated in Figs. 1 and 2, and the strip of adhesive 5 also having been applied to the marginal edge portion 4, as illustrated in Fig. 2, the opposite side portions 6 and 7 of the web are then folded inwardly toward each other as illustrated in Fig. 3, with the marginal edge portion 4 placed in overlying relation to the upper side of the marginal edge portion of the inwardly folded side portion 6. It will be seen that when placed in the relationship as illustrated the adhesive is interposed between surfaces of the marginal edge portions of the web to which the sections of coating 2 have not been applied. Hence the adhesive is effective for securing the overlapping portions together.

A tubular structure having been formed in the manner as described and as illustrated in Fig. 3, the tubular structure is then severed at intervals corresponding to the intervals of the uncoated spaces 3.

In Fig. 4 a severed sectional portion of the tubular structure shown in Fig. 3 is illustrated and it will be noted that at one end of the said section the uncoated portion 8 of one side thereof projects beyond the edge 9 of the opposite side which comprises the inwardly bent opposite side portions 6 and 7 of the web. At the opposite end of the

said tubular section the end of the side which comprises the inwardly turned overlapping side portions 6 and 7 is extended, as indicated at 10, beyond the edge indicated at 11 of the opposite side. In other words, the ends of the opposite sides of the tubular section at the opposite ends of the said section are reversely arranged or related.

The tubular section, as illustrated in Fig. 4, having been formed, a narrow strip of adhesive 12 is applied along the uncoated inner surface of the projecting end portion 8, which strip of adhesive is extended at its opposite ends over the adjoining end portions of the inwardly turned side portions 6 and 7, as indicated at 13. The adhesive having thus been applied, the end portion of the section is then bent over into position, as indicated at 14 in Fig. 5 of the drawing, and is retained in such position by the holding and binding effect of the portions of adhesive 12 and 13 previously referred to.

In Fig. 6 of the drawing I have illustrated a section of a tubular structure identical with that shown in Fig. 3 except that portions of the outer surface as well as the inner surface are provided with sections of coating 16 at intervals. The sections of coating 16 upon the outer side are located in opposed relation to the sections of coating 2 upon the inner side of the tubular structure; but, as will be noted, the uncoated marginal edge portion 17 of the outer side of the structure is located at the opposite edge portion of the web from that of the uncoated marginal edge portion 4 of the inner surface.

In commercial practice, as has been indicated already herein, the method of my invention would be carried out by means of suitable machinery, but as will be obvious, the method is capable of practice without the employment of machinery and hence it has been so described.

As I have previously indicated herein, webs or sheets of any suitable flexible material may be employed. Hence by the word "paper" employed in the specification and claims I intend to include not only paper but any other flexible sheet material which may be adapted to and suitable for the purpose of making bags.

Although I have illustrated the invention as applied to a bag in which the opposite edges thereof consist of a single fold and in which one end thereof is folded over on to an adjoining portion of the bag structure to close the same, it will be understood that the invention is not limited to bags of the specific construction shown but may be employed in the manufacture of bags of any other of the known types of structure. For example, the invention may be employed in the manufacture of bags wherein the opposite edges thereof consist of two or more pleats or folds and also may be employed in

the manufacture of bags in which the bottom and top ends thereof are or may be closed in an altogether different manner from what is illustrated in the drawing.

5 Having thus described my invention, what I claim and desire to secure by Letters Patent is:

1. The method of making a paper bag, which comprises as steps therein the placing 10 of a coating of a selected substance upon a portion of a side of a sheet of paper, the said coating being omitted from one marginal edge portion of the said side and from portions at the opposite ends of the said sheet, 15 applying a strip of adhesive to the uncoated marginal edge surface of said side, folding the opposite side portions of the said sheet inwardly to produce a tubular structure with the waterproof coating upon the inner side 20 thereof and uniting the overlapping edges of the said side by means of the said strip of adhesive, and thereafter closing one end of the said tubular structure.

2. The method of making a paper bag, 25 which comprises the placing of a coating of a selected substance upon a portion of a side of a sheet of paper, the said coating being omitted from the marginal edge portion of the said side and from the opposite end 30 portions of the said sheet, applying a strip of adhesive to the uncoated marginal edge portion of the surface of the said side, folding the opposite side portions of the said sheet inwardly and placing the marginal edge portions thereof in overlapping relation to each other and securing the same together to produce a tubular structure with the said coating interiorly thereof, placing 35 a strip of adhesive upon the uncoated portion of the said side of the said sheet at one end thereof and folding the same over on to the body portion of the said tubular structure, and securing the same in such folded-over position.

4. The method of making paper bags, 45 which comprises as steps therein the application of sections of a substance as a coating at spaced intervals upon one side of a web of paper, leaving a marginal edge portion of the said side free from such coating, applying a line of adhesive to the uncoated marginal edge portion of said side, folding the opposite side portions of said web inwardly and causing the uncoated marginal 50 edge portion of the said side to overlie the marginal edge portion of the other of the said side portions and securing the same together to produce a tubular structure, and severing the said tubular structure along 55 lines intermediate the said sections of coating.

4. The method of making paper bags, 60 which comprises as steps therein the application of sections of a substance as a coating at spaced intervals upon one side of a

web of paper, leaving a marginal edge portion of the said side free from such coating, applying a line of adhesive to the uncoated marginal edge portion of said side, folding the opposite side portions of said web inwardly and causing the uncoated marginal edge portion of the said side to overlie the marginal edge portion of the other of the said side portions and securing the same together to produce a tubular structure, severing the said tubular structure along lines intermediate the said sections of coating to produce tubular sections, and thereafter closing one end of the respective tubular sections.

5. The method of making paper bags, 70 which comprises the application of sections of coating of a selected substance successively at spaced intervals to one side of a web of paper, leaving a marginal edge portion of the surface of said side free from such coating and applying a line of adhesive to the uncoated marginal edge portion of the said surface, thereafter folding the opposite side portions inwardly and placing the marginal edges of the said opposite side portions in overlapping relation to each other and causing the said adhesive to fasten and hold the same together to produce a tubular structure, severing the said 75 tubular structure along the uncoated spaces intermediate the said sections of coating, applying a line of adhesive to the uncoated side of the edge portion of the structure adjoining one end thereof, and folding the end portion over on to the body portion of the said structure to close one end of the same.

6. The method of making paper bags, 80 which comprises the placing of sections of a coating of selected material at spaced intervals upon both sides of a web of paper, the 85 spaces between the said sections on both sides of the said web being in directly opposed relations to each other, the sections of coating of each side being omitted from a 90 marginal edge portion of the surface thereof, the edge portions of the said surfaces from which the coating of the said sections has been omitted being in reverse relation to each other at the opposite side portions of the said web, applying a line of adhesive to the uncoated marginal edge portion of the surface upon one side of the said web, folding the opposite side portions of the said web inwardly and placing the uncoated marginal edge portion having a line of adhesive thereon in overlapping relation to the marginal edge portion of the other side edge of the said sheet so that the line of adhesive 95 will be interposed between the two uncoated marginal edge portions of the surfaces upon opposite sides of the said web, securing the overlapped edges together to produce a tubular structure, severing the said tubular structure at intervals along the lines of the un- 100 105 110 115 120 125 130

coated spaces between the coated sections, and thereafter closing one end of each of the tubular sections thus produced.

In testimony that I claim the foregoing
5 as my invention I have hereunto signed my
name this 5th day of February A. D. 1929.
